UNITED STATES PATENT OFFICE.

FREDERICK NELSON, OF DRISCOLL, NORTH DAKOTA.

ROTARY ENGINE.

No. 841,425.

Specification of Letters Patent.

Patented Jan. 15, 1907.

Application filed April 6, 1906. Serial No. 310,263.

To all whom it may concern:

Be it known that I, FREDERICK NELSON, a citizen of the United States, and a resident of Driscoll, in the county of Burleigh and State 5 of North Dakota, have invented a new and Improved Rotary Engine, of which the following is a full, clear, and exact description.

The object of the invention is to provide a new and improved rotary engine which is 10 simple and durable in construction, very effective in operation, easily reversed, and arranged to utilize the motive agent to the fullest advantage.

The invention consists of novel features 15 and parts and combinations of the same, which will be more fully described herein-after and then pointed out in the claims.

A practical embodiment of the invention is represented in the accompanying drawings, forming a part of this specification, in which similar characters of reference indicate corresponding parts in all the views.

Figure 1 is a side elevation of the improvement. Fig. 2 is a plan view of the same. Fig. 25 3 is a side elevation of the improvement, showing parts in section and parts broken out. Fig. 4 is a sectional side elevation of the cylinder. Fig. 5 is a sectional plan view of the improvement on the line 5-5 of Fig. 1, and Fig. 30 6 is an enlarged rear face view of the motive-agent-controlling valve.

The cylinder A of the rotary engine is provided with intersecting bores A' A², in which are mounted to rotate the rotators B and B' 35 in rolling contact with each other, and provided with shafts C and C', journaled in the heads of the cylinder A, as plainly illustrated in Fig. 5. The outer ends of the shafts C are provided with pulleys C² for transmitting the 40 power of the engine to other machinery. The rotators B and B' are provided on their peripheral faces with gear-teeth B² B³ in mesh with each other, so that the rotators rotate in unison with each other. The rotator 45 B is provided with a diametrically-disposed integral piston-heads B⁴, adapted to pass into recesses B⁵, formed in the peripheral face of the rotator B', and the latter is provided with diametrically-disposed piston-heads B⁶, 50 adapted to pass into recesses B⁷, formed on the peripheral face of the rotator B. By reference to Fig. 3 it will be seen that the piston-heads B⁴ stand at right angles to the recesses B⁷, and in a like manner the piston-heads B⁶ 55 are arranged at right angles to the recesses B⁵, so that the piston-heads B⁴ B⁶ alternately

register with their recesses B⁵ B⁷ when the engine is running. Each of the piston-heads B⁴ is provided with sectional packing-plates D and pressed on at the piston-heads 60 by springs E, and similar springs E' engage the packing-plates at the faces of the rotators, as will be readily understood by reference to Fig. 5. Packing-plates D' are arranged in recesses E³, formed in the cylinder-heads of the cylinder A (see Figs. 4 and 5) of said packing-plates D', and pressed on by springs E² to hold the packing-plates in contact with the faces of the rotators B and B' 65 at points between the shafts C and C'. By 70 the arrangement of the packing-plates D and D' shown and described leakage of the motive agent is prevented.

In order to control the admission and exhaust of the motive agent to and from the 75 cylinder A, a valve F is provided having a casing F', in which is mounted to be turned a cylindrical valve F², provided with ports a and b, extending transversely through the valve, which latter is also provided at its rear face with a cavity c. Into the front end of the casing F leads a pipe G, connected with a boiler or other source of motive-agent supply, and from the rear end of the casing F' leads an exhaust-pipe H for carrying off the 80 exhaust motive agent. From the rear end of the casing F' also extend the pipes I and I', opening into the cylinder A at the points of intersection of the bores A' and A²—that is, the pipe I opens into the cylinder A immediately above the point of rolling contact of the rotators B and B', while the pipe I' opens into the cylinder at a distance below the point of contact of the rotators B and B'. The inner ends of the pipes I and I' are 85 adapted to register with the ports a and b, while the cavity c is adapted to register one of the ports a or b with the exhaust-pipe H. Thus as shown in Fig. 3, the port a registers at a time with the pipe I, while the pipe I' is 90 connected by the cavity c with the exhaust-pipe H; but when it is desired to reverse the engine then the valve F² is turned so as to move the port b in register with the pipe I' and to connect the pipe I by the cavity c 95 with the exhaust-pipe H. The valve F² is turned into either of the two positions mentioned by the operator, and for this purpose a shaft F³ of the valve F² is provided at its outer end with a handle J under the control 100 of the operator and provided with a locking-bolt J', adapted to engage a notched segment 105

J^2 , supported from the casing F' of the valve F . Now by the operator withdrawing the bolt J' the handle J may be swung from the left to the right or from the right to the left to change the position of the valve F^2 with a view to admit the motive agent into the cylinder A either by way of the pipe I or by the pipe I' , as above described.

The operation is as follows: When the several parts are in the position illustrated in the drawings, then the steam or other live motive agent passes by way of the pipe G , the casing F' , the port a , and pipe I into the cylinder A to exert pressure against the piston-heads B^4 B^6 to rotate the rotators B and B' in the direction of the arrows a' and a^2 . Now when next the piston-head passes the inner end of the pipe I then another impulse is given to this piston-head B^6 and its rotator B' , and in a like manner when the next following piston-head B^4 passes the pipe I then another impulse is given to this piston-head B^4 and its rotator B . When the piston-head B^4 or B^6 has passed the inner end of the pipe I' , then an exhaust takes place from the cylinder A' or A^2 by way of the pipe I' , the cavity c , and the exhaust-pipe H . When it is desired to reverse the engine—that is, to rotate the rotators B and B' in the inverse directions of the arrows a' and a^2 —then it is only necessary for the operator to swing the handle J over from the left to the right so that the position of the valve F^2 is changed, and the motive agent now passes into the cylinder A by way of the pipe I' , and consequently the motive agent now successively exerts pressure on the piston-heads B^4 B^6 to rotate the rotators B and B' in the inverse directions of the arrows a a^2 . The exhaust in the rear of the piston-heads B^4 and B^6 now takes place whenever a piston-head passes the inner end of the pipe, so that the exhaust can pass by way of the said pipe I and cavity c into the exhaust-pipe H to be carried off to a suitable place of discharge.

The rotary engine shown and described is very simple and durable in construction, composed of comparatively few parts, not liable to get easily out of order, and the en-

gine can be conveniently reversed by the operator whenever it is desired to do so.

Having thus described my invention, I claim as new and desire to secure by Letters Patent—

1. A rotary engine comprising a cylinder having intersecting bores, rotators mounted to turn in the said bores and geared together to rotate in unison, each of the rotators having piston-heads fitting recesses in the other rotator, spring-pressed packing-plates between the ends of the cylinder and the rotators and means for controlling the motive agent to and from the said cylinder. 55

2. A rotary engine comprising a cylinder having intersecting bores, rotators mounted to turn in the said bores and geared together to rotate in unison, spring-pressed packing-plates between the ends of the cylinder and the rotators each of the rotators having piston-heads fitting recesses in the other rotator 60 between the ends of the cylinder and the rotators and means for controlling the motive agent to and from the said cylinder. 65

3. A rotary engine comprising a cylinder having intersecting bores, rotators mounted to turn in the said bores and geared together to rotate in unison, each of the rotators having piston-heads fitting recesses in the other rotator, and each rotator having spring-pressed packing-plates between the rotators and the ends of the cylinder, and means for controlling the motive agent to and from the 70 said cylinder. 75

4. A rotary engine comprising a cylinder having intersecting bores, rotators mounted to turn in the said bores and geared together to rotate in unison, each of the rotators having piston-heads fitting recesses in the other rotator, and spring-pressed packing-plates in 85 grooves in the cylinder-heads of the said cylinders pressing the faces of the said rotators between the shafts thereof. 90

In testimony whereof I have signed my name to this specification in the presence of two subscribing witnesses.

FRED. NELSON.
